Attorney

UNITED STATES PATENT OFFICE.

RUDOLPH BARNES, OF YORK, PENNSYLVANIA.

DESIGN FOR WALL-PAPER.

52,625.

Specification for Design.

Patented Nov. 12, 1918.

Application filed September 14, 1918. Serial No. 254,142. Term of patent 3½ years.

To all whom it may concern:

Be it known that I, RUDOLPH BARNES, a citizen of the United States, residing at York, in the county of York and State of Pennsylvania, have invented a new, original, and ornamental Design for Wall-Paper, of which the following is a specification, reference being had to the accompanying drawing, forming a part thereof.

The figure is a view of the wall paper, showing my new design.

I claim:

The ornamental design for wall paper, as shown.

RUDOLPH BARNES.

Witness:

A. G. BARNES.
